UNITED STATES PATENT OFFICE.

WALTER STAFFORD AND ROBERT CHRISTOPHER HOLT, OF LITTLE FALLS, NEW YORK.

RACK-STITCH RIB-KNITTING MACHINE.

No. 828,818.

Specification of Letters Patent.

Patented June 19, 1908.

Application filed December 29, 1904. Serial No. 238,709.

To all whom it may concern:

Be it known that we, WALTER STAFFORD and ROBERT CHRISTOPHER HOLT, citizens of the United States, residing at Little Falls, in 5 the county of Herkimer and State of New York, have invented certain new and useful Improvements in Rack-Stitch Rib-Knitting Machines, of which the following is a specification, reference being had therein to the accompanying drawings.

Our invention relates to an improvement in knitting-machines, and we do declare that the following is a full, clear, concise, and exact description thereof sufficient to enable 15 one skilled in the art to make and use the same, reference being had to the accompanying drawings, in which like letters and numerals refer to like parts throughout,

Our invention is shown in the drawings as 20 applied to a circular machine. It has to do with the shifting of certain needles relatively to others by which the stitch or character of the fabric may be changed at will to make, for instance, what is called a "rack-stitch." 25 This we accomplish automatically by prearranged pattern mechanism. The construction which we show also has the advantage of leaving the needles largely exposed without being held throughout in grooves, so as 30 to be easily cleaned, and it also has the minimum of friction on the needles. It also has the advantage that while certain parts of the needle-dial are changed it in no wise interferes with the use of other members not 35 shown, but which the operator may wish to employ.

Other devices have been made which are able to do certain parts of the work of our improvement, but we enlarge the field of such 40 devices and improve their construction and operation.

Machines are known wherein the dial-plate is composed of parts having therebetween racking-guides, the division of the dial-plate 45 into annular parts having no advantage, but being necessary to allow the insertion of the racking-guides. These guides, however, provide for racking the needles in one direction only. We do away with this cumbersome 50 construction by employing parts of the dial-plate for racking the needles, using a construction which permits the needles to be racked in either direction. It will be seen,

further, that they can be racked a greater or less distance, as may be desired. We also 55 show a construction which minimizes the friction on the needles during their play when racked.

In distinction from other machines where certain only of the needles can be racked we 60 show a construction wherein each or any of the needle-racking sections may be moved as the feeds give the yarn to the needles to be 65 racked. We show in the drawings a machine in which each section of the dial-needles may 70 be racked when no work is done by those needles, (the yarn-feeds and the operating-cams, which are adjacent thereto, being over a different section,) in readiness for the coming of the feeds and cams in the revolution of the 75 cam-plate and its supported parts. By this construction a garment may have the rack-stitch throughout or only in certain parts.

In the drawings, Figure 1 is a plan view of a machine, showing the circular frame or bed-plate, the revolving cam-plate just within it 75 partly cut away and still within parts of the needle-dial with part of certain needles and indicating between the tips of some of them the location of the cylinder-needles, the top 80 of the cylinder cam-ring appearing just within. Fig. 1^a is a detail of part of the needle-dial. Fig. 2 is a side view, partly in section, showing the cylinder-shaft, cylinder, bed-plate, dial-plate, and dial cam-ring, together 85 with other ordinary parts and parts of our device. Fig. 3 is a side view on the other side of the cylinder-shaft from the part shown in Fig. 2 and also another part of our device. Fig. 4 is a detail plan view of certain parts of our device on line xx of Fig. 2. Fig. 4^a is a bottom 90 view of the member 7 shown in Fig. 2, showing a modified construction. Fig. 5 is a cross-section view of the same parts on line yy of Fig. 1, and Fig. 6 is a like view on line zz of Fig. 1. Fig. 7 is a face view of a member shown in Fig. 3.

Referring to the figures in detail, A represents the legs of the machine supporting the annular frame or bed B and carrying shaft C and gear D, through which power is applied 100 from pulley E to revolve the annular dial cam-plate F. This cam-ring or plate supports on studs g the radial arms G, which in turn support the cylinder-shaft H. Cylinder I, with 105 needle-grooves i and needles j , is supported

on the shaft H, resting on washer I' and is held against turning by some well-known means, while the cylinder cam-ring J is turned by the shaft H. These parts are of well-known construction and arrangement as are others indicated in the drawings and which need not, therefore, be specifically described.

On the bed B is the dial-plate. This we make in part of an outer annular ring K, which is stationary and is provided with grooved parts to confine the needles k as they are reciprocated by the cams. By limiting the grooved parts to this part of the plate which is comparatively narrow and by reducing their length to the limit of efficiency we provide the greatest possible space between the groove means and the racking means in which the needles are free to bend or swing and the least possible side friction exists in reciprocating the needles. We show the further improvement of having the lands k^a , the spacing of which provides therebetween the grooves k^b , pivotally mounted, as shown at k^c , so that as the latch end of the needles are racked the direction of the groove is correspondingly changed. This obviates entirely the side strain on the needles and any variation of the chord length of the needles by their curvature. The needles are of the usual type extending substantially the length of lands k^a , with heels to be engaged by the cams on the cam-plate, whereby they are thrust to and fro, although the needles are not all shown with the heel portion in full. Sufficient space is provided between the lands k^a to allow free play of the needles even when the needles and the lands are slightly swung, being so spaced as to allow for the slight narrowing of the interspace when the lands are swung from the true radial line of the dial. The function of the lands k^a is to permit the needles to swing slightly in the racking process without bending. The lands k^a are mounted to swing on the upper surface of ring K.

In Fig. 1^a we show a modified form of such construction, where K^a shows a sector-like plate adapted to be pivotally mounted on bed-plate B and which comprises a plurality of lands and grooves of such number as may be desired, these parts being duplicated as needed. The dial cam-plate F is of annular form and rests above ring K, being provided with cams k' to engage the heels of the needles and actuate them. The dial-plate also comprises an inner ring divided in this instance diametrically into parts L and L', which have enough space between their ends, so that each can be slid on the bed to dispose the latch end of the dial-needles one way or the other relatively to the cylinder-needles and the desired distance. These parts of the dial do not have the needle-grooves usually provided, but their surface is for the most

part plane. Near the inner edge, however, are placed blocks l, Fig. 1, which are cut away on each side, leaving a narrow face or an edge, which, with that of the block on the other side of the needle, provides means for holding and for moving the needle laterally, but not having any substantial friction-surface nor preventing the swinging or bending of the needles. Instead of the blocks pins may be inserted in the ring to answer the same purpose. The inner edge of parts L and L' are finished in usual manner, so as to provide for ordinary parts of such a machine. To hold the needles in proper horizontal plane on dial parts L and L', we provide curved strip M, which is supported above them, in this case from the feed-guides N. These feed-guides, it may be noted, are placed adjacent to the cams which actuate the dial-needles, and it will be assumed that a suitable number are employed and that the machine is provided with the usual yarn supporting and distributing parts, which are so well known that they need not be shown. The strip M may, however, be omitted, and the depending inner edge of the cam-ring may alone be relied upon to hold the needles down. On the bed at a suitable point near its margin we mount dogs 1 and 2 on pivots 1^a and 2^a, which each passes through the bed and there supports its pinion 1^b and 2^b, which mesh. The dogs are seated at an angle to each other, substantially as shown. On the lower end of pivot 1^a is fixed arm 3, though it may be made integral with pinion 1^b. It will be seen that if dog 1 is turned in it projects arm 3 and dog 2 and that when dog 2 is turned inward it turns arm 3 outward. In short, the reciprocation of dogs 1 and 2 swings the arm 3 in and out. 4 is a bell-crank pivotally mounted at 4^a on the bed-plate. One end is pivotally engaged by link 5, the other end of which is pivotally mounted on arm 3. The other end of bell-crank 4 has a pin 4^b, which projects through a slot 4^c in the bed and into one of the parts L or L' of the dial-plate, there being a set of the parts above described for each movable part of the dial-plate. It is readily seen that the swinging of either dog 1 or 2 slides the connected part of the dial-plate circumferentially on the bed. It is further seen that these sliding means are mounted one in each slidable part and about the middle. The parts which operate the levers 1 and 2 and the bell-crank 4 to shift or rack the needles are located so as to rack certain of the dial-needles only when they are idle, the knitting being then done by the other needles, which may or may not have already been racked, according to the design of the operator. Thus, supposing the cam-ring to be given a quarter-turn in either direction, Fig. 1, bracket 6 is in place to rack one segment of the inner portion of the dial-plate, the knitting being then done by the 130

needles on the opposite side of the machine, the feeds also being located to supply those needles.

To operate the dogs, we provide mechanism best shown in Fig. 2. 6 is a bracket mounted on the cam-plate and having an upward arm 6^a, the outer face of which is vertically grooved and fitted to receive and carry the vertically-moving arm 7, which has pin 7^a projecting outwardly and dog 7^b projecting inwardly and of a predetermined size for engaging one or the other of the dogs 1 and 2. Instead of the dog 7^b a cam-like disk 7^c may be employed, Fig. 4^a, being adjustable on the arm 7 by bolt 7^d to thrust the arms 1 and 2 inward a greater or less distance, according to the position of the cam-disk, and rack the needles accordingly. A spring-pin 8, of common form, is mounted on arm 6^a in contact with arm 7 and having sufficient force to hold it in given position.

At 9, Fig. 3, is a bracket mounted on the frame or bed having upward extension 9^a. This carries, vertically slidably mounted thereon, dog 10, which has at its upper end the inward extension 10^a, the face of which is transversely grooved at 10^b, the groove being widened at one end 10^c so as to engage pin 7^a when the revolution of the cam ring or plate 30 brings it to that point and dispose dog 7^b in proper plane to engage dog 1 or 2 and slide the connected part of the dial-ring. This plane is determined by proper pattern mechanism, which comprises, as here shown, pattern-chain 11, pattern-wheel 12 to carry the same, and small wheel 13, which is mounted on the lower end of dog 10 to raise or lower grooved extension 10^a according to the links of the pattern-chain passing thereunder and 40 which is caused to advance by common means.

In operation the pattern mechanism fixes the plane of dog 10 and groove 10^b, which adjusts the plane of arm 7 and dog 7^b, which turns dog 1 or 2 in, pulls out or pushes in link 5, and correspondingly slides the connected section of dial-ring. This action racks the needles—that is, it carries the inner end of the dial-needles therein mounted each to one 50 side or the other of its adjacent cylinder-needle.

The drawings show but a given form of our invention, but as modifications may be made without departing from the spirit and scope of the invention we do not limit ourselves to the particulars shown.

Having described our invention, what we claim as new, and desire to secure by Letters Patent, is—

60 1. In a circular-rib-knitting machine, the combination of a cylinder needle-bed containing cylinder-needles, a cam-ring and cams, a dial-needle bed containing dial-needles, a cam-plate and cams, the said dial-nee-

dle bed comprising an outer annular member 65 fixedly mounted and adapted to receive needles and an inner annular member divided into segments each segment being movable and having needle-engaging means thereon, substantially as described.

2. In combination in a circular-knitting machine, a cylinder-needle bed with needles, a cylinder cam-ring with cams for one or more feeds all of the same being within one-half the circumference of the ring, a dial-needle bed containing needles and composed of two annular plates one integral and the other divided into segments, a dial cam-plate with cams to correspond with the cams on the cylinder cam-ring, a bracket, a plunger adapted 70 to move in the bracket to shift the segments of the said portion of the dial-plate, means operative between the plunger and the dial-plate for said purpose, substantially as shown.

3. In a circular-knitting machine, a dial-needle bed containing needles and comprising a fixed outer annular member and an inner annular member divided into segments each movable and supporting the needles at one end and adapted to control their direction of action, a dial cam-plate with cams, and means for automatically racking the sections of the inner member of the dial, substantially as described.

4. In a circular-knitting machine, a dial 85 composed of annular members, the outer being integral and fixed and having thereon pivotally-mounted needle-guiding members and the inner of the said annular members being divided into annular sections each movable and having thereon needle-holding members whereby in the racking of the needles the latter may be swung on the dial members in either direction, means for automatically racking the sections of the inner member of 100 the dial, substantially as shown.

5. In a knitting-machine, a dial-plate comprising two separate annular members supporting the needles at each end the inner one provided with means for engaging the 110 ends of the needles at the side and being radially divided into parts and means for automatically shifting the said parts for racking the needles in either direction, substantially as shown.

6. In a knitting-machine, a dial-plate comprising a series of annular members, the outer being fixed and provided with a series of sector-like lands adapted to engage the needles, the said lands being pivotally mounted, means 120 for automatically racking the needles by contact of such means at the latch ends of the needles, substantially as shown.

7. In a circular-knitting machine provided with cylinder and dial knitting means, 125 means for automatically racking the dial-needles, the said means comprising notched guides engaging the needles, a bracket, a ver-

tically-adjustable plunger therein having a horizontal lug thereon, a guide operated by pattern mechanism and adapted to engage the said plunger and adjust its operative position, a series of lever connections with the said notched guides operative by contact with the plunger-lug therewith to swing the same to rack the needles in either direction, and a pattern mechanism, substantially as shown.

8. In a circular-knitting machine, a dial supporting the needles in their operation and composed of two annular members, the outer integral and the inner formed of a plurality of parts each movable and provided with needle-engaging means to rack the dial-needles and means for automatically swinging the parts of the inner dial member to rack the needles, substantially as shown.

20 9. In a circular-knitting machine, a dial composed of a fixed outer annular member and of an inner member of sector-like parts having thereon means for swinging the inner end of the needles on the dial members, the outer of said dial members having swinging grooved parts engaging the needles, substantially as shown.

10. In a circular-knitting machine provided with a dial and dial-needles, means engaging the said needles to permit racking the same by swinging them in either direction, and means for racking the needles, the said means comprising an adjustable plunger with a lug to engage the racking means, substantially as shown.

35 11. In a circular-knitting machine, a dial-plate comprising two annular members, the outer being fixed and adapted to receive needles and having pivotally-mounted members therefor and the inner composed of a plurality of sections movable in succession to rack the needles and having needle-engaging means

thereon; and means for moving the sections in either direction, substantially as shown.

12. In a circular-knitting machine, a dial composed of separate ring portions, one being fixed and having thereon swinging grooved parts for the needles and the other portion being divided radially into parts each movable and having needle-engaging means to swing the needles in either direction to make a rack-stitch, substantially as shown.

13. In a circular-knitting machine, a dial-plate with needles and composed of two annular plates one integral and the other divided into sectors each independently movable, a dial cam-plate with cams, a plunger having a lug thereon and means engaging the lug and connected with the sectors of the dial to swing the same in either direction and to a 60 degree depending upon the size of the lug on the plunger, substantially as shown.

14. In a knitting-machine, a dial-plate composed of two annular members, the inner one being radially divided into parts each 65 being movable circumferentially and having needle-engaging means and the outer one being fixed and provided with swinging means to engage the needles as reciprocated, substantially as shown.

15. In a circular-knitting machine, a dial comprising a fixed ring and an inner ring composed of sections movable circumferentially in succession; and means for moving the said sections to and fro, substantially as 75 shown.

In testimony whereof we affix our signatures in presence of two witnesses.
